UNITED STATES PATENT OFFICE.

EZRA S. BUCKNAM, OF LLANERCH, PENNSYLVANIA, ASSIGNOR TO JOHN A. BRILL, OF PHILADELPHIA, PENNSYLVANIA.

GONG.

SPECIFICATION forming part of Letters Patent No. 784,382, dated March 7, 1905.

Application filed May 24, 1904. Serial No. 209,453.

To all whom it may concern:

Be it known that I, EZRA SANGER BUCKNAM, a citizen of the United States, and a resident of Llanerch, State of Pennsylvania, have invented certain new and useful Improvements in Gongs, of which the following is a specification.

My invention relates to gongs particularly adapted for railway-cars, and pertains to the class of gongs adapted to be operated by one or more cords.

The objects of my invention are to produce a gong in which the action of the striking-lever will be quick and its return thrust facilitated and the parts so formed that the cord or cords may be attached to the gong at a point nearest the direction from which the cord approaches instead of being connected with the striker-arm and returning underneath the bell, as in former devices.

It is my further object to produce means whereby one gong may answer the purpose of two in the present practice.

Heretofore it has been customary to have two gongs attached to the hood at each end of the railway-car, and this has been especially necessary in open street-cars, where it is necessary to have a cord running along the side of the car.

By means of my improved arrangement the cords on each side of the car may both lead to a single bell at each end of the car and adapted to operate the gong from either side of the car.

Further advantages of my invention reside in the striking-plunger and in the further details of construction, which will be more fully hereinafter explained, and further set forth in the claims.

In the drawings forming part of this specification, in which similar numerals of reference indicate corresponding parts throughout the several views, Figure 1 is an inverted plan view of my improved gong with the cord arrangement detached. Fig. 2 is a cross-section taken on the line 2-2 of Fig. 1 looking in the direction of the arrows. Fig. 3 is an end view of Fig. 1, taken from the right-hand end,

Fig. 4 is a similar view taken from the opposite direction with the cord mechanism removed. Fig. 5 is a section taken on the line 5-5 of Fig. 2, looking in the direction of the arrows. Fig. 6 is a side elevation, partly in section, showing the arrangement of the cord mechanism. Fig. 7 is a plan view of Fig. 6 with a portion of the gong cut away. Fig. 8 is an end view of Fig. 7, and Fig. 9 is a section on the line 9-9 of Fig. 8 looking in the direction of the arrows.

As the form of gong to which I have applied my improvements is commonly used for attaching to the ceiling of a car-hood, I have illustrated it adapted to that particular use. For that purpose I have provided a bracket or support 1, which may be of any suitable shape. As illustrated herein, the bracket is provided with ends 2, which may be attached to the ceiling by means of screws or other means, and an outwardly-bent portion 3, forming a space to receive the gong.

The gong 4, which is of any desired shape, is attached to the bracket by any suitable means, such as the bolt 5, which passes through the bracket and the gong in the usual manner. Near one end of the bracket I provide an aperture in which the plunger 6 fits and moves therein. The novel feature of the plunger resides in forming an enlargement 7 near the upper end, which holds the plunger in place in the bracket, and a narrower or pointed end 7^a, adapted to come in contact with the rim of the gong. This gives the plunger weight and at the same time a small striking-surface.

One of the novel and important features of my invention resides in the striking means, which, as I have illustrated it, consists of a striking-lever 8, having a weighted end 9, which is preferably turned at an angle to the lever. The lever is fulcrumed at any desired point, such as 10, to a support, which I prefer to be the supporting-bracket, and so mounted that the end 9 will be thrust in contact with this plunger 6, the upward thrust of the lever being determined by the stop 11, which comes in contact with part of the bracket. In order

that the sound of the gong will not be muffled by continuous metallic connection, I prefer to so construct these parts that the stop 11 will come in contact with the bracket and stop the 5 thrust of the lever before the plunger comes in contact with the gong, thus permitting the plunger to drop back from the gong part way before the lever returns to its former position.

In order to produce a quick and efficient 10 means for tripping the striking-lever, I provide a toe, such as 12, connected with the lever and which I prefer to make integral therewith. The upper surface 13 of said toe is concave and is designed to coöperate with a 15 convex surface formed on the toe of a tripping-lever 14 in the manner to be described.

As herein shown, the tripping-lever 14 is fulcrumed at 15 to the bracket, and its toe 17, having the convex surface 18, overlies the toe 20 12 of the striking-lever. The tripping-lever is provided at the end of its short arm with an eye 16 to receive the bell-cord. The two 25 surfaces 13 and 18 on the toes of the striking and tripping levers, respectively, are constructed so as to be conjugate to each other—that is to say, so that they will roll upon each other in the manner of two gear-teeth in mesh without any sliding friction. The effect of 30 this construction is to cause the point of contact of the two toes 12 and 17 to move back and forth between the pivots 10 and 15 of the striking and tripping levers as said levers swing upon their pivots. In this way the leverage of the toe of the tripping-lever on 35 the toe of the striking-lever is greatest at the commencement of the movement and the motion of the striking-lever is progressively accelerated and reaches its maximum at the moment when the hammer 9 strikes the plunger 40 6.

A suitable stop, such as the piece 19, is provided, against which the tripping-toe may rest when the parts are in their normal or resting position.

In order that the gong may be operated by 45 a plurality of cords diverging from the longitudinal direction of the bell, I provide, as shown in Figs. 6 to 9, inclusive, a means for connecting and operating the several cords in connection with the single tripping-lever. This part of my invention consists in mounting one or more sheaves or rollers, such as 20 and 21, by means of a bracket, such as 22, either to the car-hood or, as illustrated in Figs. 50 2 and 6, the bracket may be secured to the bracket which supports the gong. These sheaves are preferably mounted one over the other, by means of an axle 23, in the bracket, so as to be in alinement with the longitudinal 55 direction of the gong. One or more cords, such as 24 and 25, may be attached, by means of the single hook 26 or other suitable means, to the eye of the tripping-lever and pass in reverse directions around the sheaves, so that

one cord may pass to one side of the car, while 65 the other passes to the opposite side, it being understood that the gong is by preference mounted at about the center of the car transversely.

The object of the two sheaves, as it will be readily understood, is to give the striker-arm 70 a direct pull by means of the separate cords which diverge in different directions and by which the cords on opposite sides of the car are each adapted to a single gong.

For the purpose of retaining the cords in 75 their proper place on the sheaves I provide a guard, such as 27, attached to the bracket and provided with an inturned flange 38. The bracket passes around the cords just in front of the point where the latter cross after leaving the sheaves, the flange 38 serving to separate the cords from each other.

From the foregoing the advantages and operation of my invention will be readily understood. Assuming the parts to be in the initial position, (indicated in Fig. 2,) when the arm 16 of the tripping-lever 14 is pulled or otherwise moved to the left the rocking surface 18 of the toe 17 rocks on the curved surface 13 of the toe 12, whereby both the surfaces 13 and 18 have a rolling contact and a downward motion. When in the initial position of Fig. 2, the distance from the point of contact of these two surfaces to the pivot 15 is a minimum and to the pivot 10 is a maximum. As the surface 18 moves downward this point of contact with the surface 13 moves with a rolling and not a sliding movement nearer the pivot 10 and from the pivot 15 until the stop 11 impinges against the screw-head 85 of the gong-fastener 5 when this movement terminates with the distance from this point of contact is a minimum with regard to the pivot 10 and a maximum with regard to the pivot 15. As soon as the bell-cord is released the weight 90 of the end 9 is sufficient to cause the surface 13 to raise the surface 18 with a rolling motion, the point of contact of these surfaces returning with a rolling movement to the initial position when the bell-crank or tripping-lever 100 14 has its toe 17 resting against the stop 19. As the distance from the pivot 15 to the point of contact of the toes 17 and 12 is a minimum when in the initial position the striking-lever 8 is started with a minimum effort, and as its 105 inertia is overcome and as the point of contact moves from the pivot 15 nearer to the pivot 10 the velocity of the head or end 9 of the striking-lever 8 is rapidly accelerated until it strikes a smart blow against the plunger 6, 110 whereby the gong is sounded. The weight of the end 9 is always sufficient to retrieve the bell—that is, place it in condition to ring again—because the distance from the pivot 10 to the point of contact of the surfaces 13 and 115 18 is a minimum, and these surfaces engage with a rolling and not a sliding contact, whereby friction is reduced to a minimum, and a

lubricant between these surfaces is unnecessary. The movement of the arm 16 is very slight, about a quarter of an inch or less in the ordinary bell, so that the bell will always 5 ring even with the slightest pull on the cord and will always retrieve for this and the other reasons given above, a result not obtained with any other bell. In addition to the above advantages this bell has the additional ones 10 of requiring no springs to retrieve the bell, as is common in the art, nor does it require any particular attention, and, furthermore, it will stand an indefinite amount of rough use, as the wearing parts engage without friction, 15 and the bell-cord can never get caught by the striking-lever.

My invention is adapted for use in a gong where the plunger is omitted, it only being necessary to arrange the parts so that the lever 20 will strike directly against the gong.

While I have shown and described a specific means for carrying out my invention, I do not wish it to be understood as limiting the scope of the annexed claims thereby, as alterations may be made without departing from the spirit of my invention.

Having described my invention, what I claim is—

1. In a bell or similar device, the combination with a striking-lever comprising a hammer-arm and an actuating-toe, of means to swing said striking-lever constructed and ar-

ranged to act on said toe at points successively approaching the pivot of said striking-lever.

2. In a bell or similar device, the combination of a striking-lever and a tripping-lever, each of said levers having an actuating-toe, said toes having coöperating curved surfaces constructed and arranged to roll on each other when the levers are actuated.

3. In a bell or similar device, the combination of a striking-lever having a hammer-arm and an actuating-toe provided with a concave surface, a tripping-lever to actuate said striking-lever having an actuating-toe provided with a convex surface, said surfaces being constructed and arranged to roll on each other during the movement of said levers, whereby the distance of the point of contact of said surfaces from the pivot of each of said levers 50 constantly varies during the movement of said levers.

4. In a bell or similar device, a gong and gong-striking mechanism, a pair of cords attached to said gong-striking mechanism, a pair 55 of sheaves on a common axis, over which sheaves said cords pass and means for supporting said sheaves.

Signed this 5th day of May, 1904.
